UNITED STATES PATENT OFFICE

1,920,275

METHOD OF FORMING METAL TYPE TUBES

Frank H. Poeppelmeier, Dayton, Ohio, assignor, by mesne assignments, to Set-O-Type Manufacturing Company, Cleveland, Ohio, a Corporation of Delaware

Original application May 13, 1927, Serial No. 191,099. Divided and this application February 5, 1931. Serial No. 513,501

2 Claims. (Cl. 153—2)

This invention relates to new and useful improvements in the method of forming tubes from metal.

The application is a division of my application 5 which resulted in United States Patent No. 1,762,835, granted June 10, 1930.

It is the principal object of my invention to provide a method of economically and expeditiously forming from metal, tubes such as type 10 tubes. This method contemplates, first shearing a strip of metal to the required length, with an ear formed on one end and a pinched-in or pronged portion at its other end, and then by 15 three successive steps bending it to assume a form having a flat back and channeled front to receive T-shaped type for passage therethrough.

In the accompanying drawing illustrating the means for carrying my method into effect, Figure 1 is a sectional view taken through the feeding 20 rolls, Figure 2 is a sectional view through the shearing rolls, Figure 3 is a sectional view taken through the second feeding rolls, Figure 4 is a sectional view taken through the first forming rolls, Figure 5 is a sectional view taken 25 through the second forming roll and disc, Figure 6 is a sectional view taken through the final forming rolls, Figure 7 is a side view of the type tube formed by my machine, and Figure 8 is a dia- 30 grammatic view showing the shearing unit of my machine.

A complete description of the machine for carrying out my method of forming tubes from metal appears in the mentioned above United State Patent No. 1,762,835.

My method for forming tubes, and more particularly type tubes, will now be described.

A metal strip 78 from a roll (not shown) is directed between the feed rolls 42 and 43, and by 40 them is fed to the shearing rolls 33 and 35, the retaining disc 34 being shown attached to the roll 33.

Referring to Figure 8, it will be observed that 45 there is provided in the periphery of the roll 33 a recess into which is fitted a female die 85 and a stripper 86 resting on a rubber cushion 87. In a recess in the periphery of the upper roll 35 there is fitted a male die 88 which is formed and located to co-act with the female die 85 to 50 cut the metal strip 78 into proper lengths, with an ear 89 formed on one end of each strip and terminating at its other end in a pinched-in or pronged portion 90. (See Figure 2.)

The ear 89 may be bent up to close its 55 respective end of the tube after the type have been inserted therein, while the pinched-in or pronged

end 90 permits the side walls of the other end of the tube to be collapsed to prevent the type from falling out of that end. The shearing action of the male die 88 acting against the female die, forms the ear on one end and the prongs on the 60 other end of each type tube blank which they cut from the metal strip. (See Figure 3.)

The strip so sheared and formed by the rolls 33 and 35 is directed between the next rolls 9 and 18. The roll 9 has a grooved periphery 10 which 65 forms a wide annular projection 19 formed on the roll 18, is adapted to enter.

After passing between these rolls, the strip is fed by them to the first forming rolls 43 and 50. The roll 43 has a grooved periphery 70 49 into which the metal strip is forced by a wide annular projection 51 on the roll 50. These rolls 43 and 50 form each metal strip with a flat bottom 91 and two slightly upturned sides, 92, 92. (See Figure 4.)

The roll 59 having a grooved periphery 60, and the disc 61, which next receive the partly formed strip, give to the latter the more pronounced curvature shown in Figure 5. The 80 still partly formed metal strip then passes to the third forming rolls 68 and 70. The periphery of the roll 68 is formed with two spaced flanges 69, 69 which enter a concaved periphery 71 on the roll 70 to crimp the curved sides of the tube 85 93 to its final shape, as shown in Figures 6 and 7.

Having described my invention, I claim:

1. The herein described method of forming a type tube from metal, which consists in first shearing a metal strip to the length required, with an ear formed on one end and prongs at 90 its other end, and then bending said strip to channel form.

2. The herein described method of forming a type tube from metal, which consists in first shearing a metal strip to the length required, with an ear formed on one end and prongs at 95 its other end, then bending said strip to channel form with a straight bottom, then bending the side walls of said metal strip further toward 100 each other, and then bending the walls still further together to form a type tube.

FRANK H. POEPPELMEIER.
